(57) **CLAIM**

The ornamental design for a part of an automobile as shown and described.

DESCRIPTION

FIG. 1 is a front perspective view of the part of an automobile showing my design;

FIG. 2 is a rear perspective view thereof;

FIG. 3 is a front view thereof;

FIG. 4 is a lateral view thereof;

FIG. 5 is a rear elevation view thereof; and,

FIG. 6 is a top plan view thereof.

Portions of the automobile shown in broken lines are not part of the claimed design.

The present design is directed to a part of an automobile, and more specifically to a rear portion of the automobile, including a rear trunk and a spoiler.
